EXTRUSION DEVICE

Charles T. Walter, Chicago, Ill., assignor to Industrial Patents Corporation, Chicago, Ill., a corporation of Delaware

Application December 21, 1933, Serial No. 703,351

30 Claims. (Cl. 25—8)

This invention relates to an extrusion die. One of the objects of the present invention is to provide an extrusion nozzle adapted to form tubular soap.

Another object of the invention is to provide an extrusion nozzle adapted to form ribbon soap.

Other objects of the invention will be apparent from the description and claims which follow.

It will be understood, of course, that the extrusion die or nozzle of the present invention may be utilized for any desired purpose and the device will be discussed in this specification as used in the formation of tube soap or ribbon soap such as is more particularly described and claimed in my copending application entitled Soap product and method of making the same, filed December 21, 1933, Serial No. 703,350, by way of illustration and not by way of limitation.

Referring now to the drawings:

Figure 1 is a view, partly in section, of one embodiment of the present invention.

Figure 2 is a plan view of the upper portion of the device shown in Figure 1.

Figure 3 is a sectional view taken on line 3—3 of Figure 1.

Figure 4 is a sectional view taken on line 4—4 of Figure 1.

Figure 5 is a view, partly in section, of another embodiment of the present invention.

Figure 6 is a view, partly in section, of another embodiment of the present invention.

Figure 7 is a fragmentary view, partly in section, showing a side view of the extrusion pin of the device shown in Figure 6.

Figure 8 is a plan view of the extrusion pin and die opening shown in Figure 7.

Figure 9 is a cross-sectional view of tube soap formed with the extrusion nozzle of the present invention.

Figure 10 is a cross-sectional view of ribbon soap formed with the extrusion nozzle of the present invention.

Figure 11 is a plan view of another variation in the shape of the extrusion pin illustrated in Figure 6.

Figure 12 is a perspective view, partly broken away, of a section of tube soap of the type shown in cross section in Figure 9.

Figure 13 is a view, partly in section, of another embodiment of the present invention.

Referring now more particularly to Figures 1,

2, 3 and 4:

Within casing 1 is a chamber 2 into which soap in a plastic, semi-liquid condition may be forced under hydraulic pressure through pipe 3.

Pipe 3 is threaded in boss 4. Spindle 5 is rotatably mounted within casing 1 and terminates in an extrusion pin at 6. It will be noted that bearing 7 is a double row combination radial and thrust ball bearing which performs the dual function of guiding the upper end of the spindle 5 in a radial direction and takes the thrust load imposed on spindle 5 by virtue of the hydraulic pressure within chamber 2.

Ball bearing 8 is positioned comparatively close to the lower end of the spindle and performs merely the function of guiding the lower end of the spindle 5 in a radial direction. Bearing 8 is not required to take any thrust load and may be of either the single row or double row type. However, in the drawings it is shown of the double row type. End plate 9 which is screwed into casing 1 by threads 10 and which cooperates with the casing to form a housing, is provided with an extrusion orifice 11 at the base of conical recess 12 in which fits conical end 13 of the spindle 5. The end plate 9 which is provided with the extrusion orifice constitutes an extrusion plate. Wrench recesses 14 and 15 are provided in end plate 9 to facilitate removal and insertion of the end plate.

End plate 9 is guided and held rigidly in a central position with respect to the body portion by means of cylindrical guiding portions 16 and 17. Shoulder 18 limits the depth to which the plate 9 may be screwed into the casing 1. Stuffing box 19 is a cast iron bushing having a press fit in the bore 20 of the body. The bushing 19 is preferably machined on the inside so as to form a very close running fit with the enlarged portion 21 of the rotating spindle 5. Stuffing box bushing 19 has an internal groove 22 vented to the outside surface of casing 1 by outlet opening 23, thus preventing soap from being forced from chamber 2 into the upper portion 40 of the device above hole 23.

Nut 24 is screwed into casing 1 by threads 25 and serves to carry the thrust transmitted through bearing 7. It will be noted that nut 24 is designed to screw down solidly against shoulder 26. Flat surfaces are preferably provided on the portion 27 of nut 24 to provide suitable bearing surfaces for a wrench. The upper extremity 28 of nut 24 is machined to a smooth surface to provide a bearing for sprocket 29 which contains a suitable bronze bushing 30. Bushing 30 is designed to permit the sprocket 29 to rotate freely about bushing portion 28 of nut 24. The driving end 31 of the spindle 5, passes up through concentric hole 32 in nut 24.

A slight amount of clearance between the driving end 31 of the spindle and nut 24 is indicated at 33.

The amount of clearance is not important, it 5 being merely desirable that driving end 31 of spindle 5 does not contact the surface of concentric hole 32 in nut 24 since nut 24 is not utilized as a bearing for spindle 5. Flange 34 is firmly attached to the upper end of spindle 5 by 10 means of key 35. Leather washer 36 is provided to transmit driving force from sprocket 29 to flange 34 through driving pins 37 and 104.

It will be noted by reference to Figure 2 that 15 there are three pins 37 and three pins 104. Pins 31 are firmly fastened in flange 34 and project into holes in the leather washer. Pins 104 are firmly fastened in sprocket 29 and project into holes in leather washer 36. This construction 20 provides a flexible connection between driving spindle 5 and driving sprocket 29. This flexible connection avoids the possibility of imposing a bending moment on the rotating spindle and the bearings in which it is mounted. By virtue of 25 this construction, all bending and shearing forces resulting from the chain drive on the teeth 38 of sprocket 29 are resisted by bearing 39 and are transmitted directly to the rigid body of casing 1, and consequently only a pure torque is transmitted to the spindle.

30 A breather hole 40 runs the entire length of spindle 5 with an opening at the end of extrusion pin 6. A flange 109 having holes 10 and 111 is integral with casing 1 and is provided in order that the entire device may be bolted against 35 any suitable supporting member.

In operation, plastic soap is forced under hydraulic pressure through pipe 3 and thence into chamber 2. From chamber 2 the soap passes 40 through opening 41 between the balls 42 in bearing 8. The soap then passes into chamber 43, thence through the conical passage 12 which leads to the extrusion opening 11 and is distributed uniformly around the spindle head 13.

I have found that it is important that the 45 extrusion pin 6 be very accurately centered in the extrusion opening 11. If the pin is not accurately centered in the hole, an annular passage is formed through which the soap flow is not uniform at all points, bringing about a definite difference in the resistance to flow at various points. Those points about the annular orifice which are closest together, offer a much higher resistance is formed through which the soap flow is not uniform at all points, bringing about a definite difference in the resistance to flow at various points. Those points about the annular orifice which are closest together, offer a much higher resistance to flow than those points which are wider apart. The result of such non-uniformity of resistance 50 around the orifice is the production of a tube with non-uniform walls issuing from the nozzle orifice at a higher velocity along those points of minimum resistance to flow than at those points having a greater resistance to flow. In practice, this condition manifests itself in a tube which issues from the nozzle deflected at a considerable angle to the axis of the nozzle, the inclination of the tube being toward the side of minimum wall thickness or minimum velocity of flow. A further result of this lack of concentricity between the inner and outer walls of the tube is to produce a tube which is decidedly weakened on one side and which, therefore, shows 55 holes or breaks along the thin side at intervals.

When the extrusion pin is accurately centered in the hole so as to produce a tube with substantially concentric inner and outer walls, the tube issues from the nozzle along the line of the axis 75 of the spindle. Under these conditions, soap may

be formed into perfectly shaped tubes of uniform mechanical strength at all points.

Furthermore, this may be done at a high rate of speed.

Since the accuracy with which the extrusion 5 pin may be centered in the hole depends upon precision of manufacture of the ball bearing, I prefer to use ball bearings held to inspection limits of .0002". If it is desired to form a tube 10 soap and it is desired to form tubes at the rate of 100 feet per minute, I prefer to rotate the spindle at the rate of 100 R. P. M. In such case it is sufficient merely to leave the breather tube 40 open to prevent collapse of the tube. If it is desired to operate the device at a greater rate of 15 speed, for example to produce tubes at the rate of 400 feet per minute, I rotate the spindle at the rate of 100 R. P. M. and supply air at a pressure of about 6 to 10 inches of water to the breather tube. If it is desired to form ribbons, it is desirable 20 to pull a vacuum of about $\frac{3}{4}$ inch of water on the breather tube in order to effectually collapse the tube to a flattened ribbon.

Although in practice I prefer to rotate the spindle 25 at the rate of about 100 R. P. M., I have found in experimental work that speeds as low as 10 R. P. M. are satisfactory.

It will be noted that the upper bearing 7 which is preferably the more heavily loaded of the two 30 bearings since it takes the end thrust of the spindle, is mounted so as to be permanently supplied with a suitable lubricant in the race 44. The lower bearing 8 runs continuously in an everchanging mass of plastic soap.

Referring now particularly to Figure 5 in which 35 there is shown a more simple embodiment of the present invention.

This device comprises a casing 45, provided with an extrusion hole 46 in which is fitted extrusion pin 47 integral with rotatable spindle 52. 40 Bearings 48 and 49, integral with spindle 52, are adapted to rest against end thrust shoulders 50 and 51 respectively and rotate within casing 45. The thrust shoulder 51 consists of an annular boss formed integral with the cover 54 and extending 45 into the upper end of the casing 45. Extension shaft 53, also integral with spindle 52, is brought out through cover 54, through stuffing box 57. Stuffing box 57 is provided with bushing 58 held in place by cap 59 threaded through the body 54 as at 60. Cover 54 is affixed to casing 45 as by screws 55 and 56. Shaft 53 may be rotated by any convenient means and is provided with a breather hole 61 which passes through extrusion pin 47 to permit air to enter the extruded soap 55 tubes.

In this embodiment of the invention, soap enters through pipe 62, passes into chamber 63, thence through openings 64 in bearing 48, 60 through chambers 65 and 66 and out extrusion hole 46.

It will be noted that the clearance space at 104⁴ is less than the annular space between pin 47 and opening 46. This provides a filtering action wherein large particles of foreign material 65 are trapped at 104 and are not permitted to pass on to the annular extrusion opening at 46. This feature, of course, is only of importance where the soap stock has not been adequately filtered.

Referring now more particularly to Figure 6: 70

In this figure is depicted a cross-sectional view of an embodiment of the present invention with provisions for increasing the area of extrusion opening without materially affecting the wall thickness of the finished tube. 75

Figure 7 shows a section through the extrusion opening of the device shown in Figure 6 with the pin in place, the section shown in Figure 7 being taken at right angles to the section of Figure 6.

5 Figure 8 is a view looking into the extrusion opening shown in the device in Figure 6.

Figure 11 is a view looking into the extrusion opening of a device similar to the one shown in Figure 6 but provided with a variation in the form 10 of the pin.

Again returning to Figure 6:

This device is provided with a casing 67 having an extrusion opening 68 in which is centered pin 69 which is integral with spindle 70, provided 15 with bearings 71 and 72. Bearing 71 rides on shoulder 73 and against inner wall 74. Bearing 72 rides against inner wall 74 and takes the end thrust against bearing surface 75 of cap 76 which is secured to casing 67 as by screws 77 and 78. Spindle 70 may be driven by any convenient means such as gear 79. It will be noted 20 that a breather opening 80 is also provided running through the entire length of spindle 70 to the end of pin 69.

25 It will be noted by reference to Figures 7 and 8 that the extrusion pin 69 is partly cut away. In Figure 11 the cut away pin is shown in the form of a central web.

30 In practice, however, I prefer to use the cylindrical type of pin.

Referring now particularly to Figure 13:

This figure shows an embodiment of the present invention which is preferred in ordinary commercial practice. Although an open ball bearing located intermediate the receiving chamber and the extrusion opening mills soap material passing therethrough, I have found that soap stock has a deleterious effect on ordinary ball bearings and cuts down their life. It will be noted that the modification of the present invention depicted in Figure 13 is provided with two ball bearings but that both bearings are sealed from the soap. This construction renders the modification shown in Figure 13 most desirable for use in extruding ordinary commercial soap stock.

45 Due to the similarity between the embodiment of the invention shown in Figure 1 and the embodiment of the invention shown in Figure 13, similar parts in these two figures are designated by similar reference characters, independent reference characters being used in Figure 13 only where the parts differ in construction or function.

In Figure 13 casing 1 is provided with boss 4 into which is threaded inlet pipe 3 through which a product such as soap in a plastic form may be fed to the device. Spindle 5 is rotatably mounted within casing 1. It will be noted that bearing 7 is a double row combination radial and thrust ball bearing which performs the dual function of guiding the upper end of the spindle 5 in a radial direction and takes the thrust roll imposed on spindle 5 by virtue of the hydraulic pressure within chamber 81, which receives soap through passage 82. Ball bearing 83 is positioned relatively close to the lower end of the spindle. This bearing is not required to take any thrust but acts merely as a radial bearing to guide the spindle and assure centering of the pin 6 in extrusion opening 11. This bearing may be of either the single or double row type but as shown in the drawings is of the single row type. End plate 9 is screwed into casing 1 by threads 10 provided with the extrusion orifice 11 at the base of conical recess 12 in which fits conical 70 end 13 of the spindle 5. Wrench recesses 14 and

15 are provided in end plate 9 to facilitate removal and insertion of the end plate.

End plate 9 is guided and held rigidly in a center position with respect to the body portion by means of cylindrical guiding portions 16 and 17. Shoulder 18 limits the depth to which the plate 9 may be screwed into the casing 1. Spacer bushing 85 is a cast iron bushing having a light press fit in the bore 20 of the body. It will be noted that there is a space 86 between the spindle 5 and spacer bushing 85.

Nut 24, which is screwed into casing 1 by threads 25, serves to carry the thrust transmitted through bearing 7. It will be noted that nut 24 is designed to screw down solidly against shoulder 15 26. Flat surfaces are preferably provided on the portion 27 of nut 24 to provide suitable bearing surfaces for a wrench. The upper extremity 28 of nut 24 is machined to a smooth surface to provide a bearing for sprocket 29 which contains 20 a suitable bronze bushing 30.

Bushing 30 is designed to permit the sprocket 29 to rotate freely about a bushing portion 28 of nut 24. The driving end 31 of the spindle 5 passes up through a concentric hole 32 in nut 25 24, a slight amount of clearance between the driving end 31 of the spindle and nut 24 being indicated at 33. The amount of clearance is not important it being merely desirable that driving end 31 of spindle 5 does not contact the surface 30 of concentric hole 32 in nut 24 since nut 24 is not utilized as a bearing for spindle 5.

Flange 34 is firmly attached to the upper end of spindle 5 by means of key 35. Leather washer 36 is provided to transmit driving force from 35 sprocket 29 to flange 34 through driving pins 37 and 104. It will be noted by reference to Figure 2 that there are three pins 37 and three pins 104. Pins 37 are firmly fastened in flange 34 and project into holes in the leather washer. Pins 104 40 are firmly fastened in sprocket 29 and project into holes in leather washer 36.

This construction provides a flexible connection between driving spindle 5 and driving sprocket 29. This flexible connection avoids the 45 possibility of imposing a bending moment on the rotating spindle and the bearings in which it is mounted. By virtue of this construction all bending or shearing forces resulting from the chain drive on the teeth 38 of sprocket 29 are 50 resisted by bearing 39 and are transmitted directly to the rigid body of casing 1 and consequently only a pure torque is transmitted to the spindle. A breather hole 40 runs the entire length of spindle 5 with an opening in the end 55 of extrusion pin 6. This breather opening is provided with a suitable oil shield, hereinafter described. A flange 109 having holes 110 and 111 is integral with casing 1 and is provided in order that the entire device may be bolted against 60 any suitable supporting member, which preferably comprises a closed, oil retaining, chain box, hereinafter described.

Stuffing box 87 prevents the passage of soap along the portion 88 of spindle 5 and into bearing 83. Stuffing box 87 consists preferably of a plug 89 of brass or other suitable metal which is press fit into the casing 1. The outer end of the hole 88 through plug 89 is counter-bored and filled with a soft metal such as solder as at 91. 70 In the construction of the stuffing box, this soft metal is then carefully bored concentric with the outside of the plug to a diameter slightly larger than the diameter of the pin. The remainder of hole 88 through plug 89 is likewise bored concen- 75

tric with the outside of the plug but to a diameter slightly larger than the bore through the soft metal 91, but only large enough to provide a reasonably free running fit to prevent binding 5 between the pin and the plug. Above the soft metal ring 91 are two grooves 92 and 93 vented through plug 89 by two sets of holes 94 and 95, communicating with external grooves 96 and 97. External grooves 96 and 97 are in turn vented 10 to the atmosphere through two series of holes 98 and 99. Recess 100, immediately above groove 93, contains leather washer 101, which has a slight press fit around spindle 5 and is held in place by brass washer 102 which also prevents 15 leather washer 101 from coming in contact with the rotating inner race of ball bearing 83. The force asserted against the surface of plug 89 by the hydraulic pressure of the soap in chamber 81 is resisted by a thrust action through the material of plug 89 which is transmitted to washer 102, which in turn transmits it to the outer race of ball bearing 83, which in turn transmits it to 20 spacer bushing 85 which carries it to the outer race of ball bearing 7 through which it is transmitted to nut 24.

From this it will be apparent that none of the thrust load imposed upon plug 89 is transmitted to any of the moving parts of the device.

The assembly of stuffing box 87 is designed to 30 prevent the flow of soap into bearing 83. It will be seen that this is accomplished by grooves 92 and 93 in combination with the venting arrangement.

The extrusion device shown in Figure 13 is 35 shown as mounted in a box 105 provided with a cover 106 held in place as by bolts 107 and 108. Oil box 105 is of the type described and claimed in my copending application entitled Drier conveyor, Serial No. 703,348, filed December 21, 1933. Flange 109 is affixed to box 105 as by bolts 112 40 and 113. Sprocket 29, driven by a roller chain, not shown, operating a plurality of extrusion devices, is bathed in oil 114.

It will be seen that oil 114 communicates with 45 the interior of the extrusion device through hole 115 in nut 24, the oil finding its way down through bearing 7 and space 86 to bearing 83.

The embodiment of the invention shown in Figure 13 is provided with an oil shield of the type described in my copending application entitled Drier conveyor, Serial No. 703,348, filed December 21, 1933. Oil shield 116 consists of a metallic plate 117 mounted on a suitable extension 118 of spindle 5. Sheet metal shield 119 is 55 fastened to plate 117 by small posts 120.

Shield 119 provides a cover 121 with an integral depending flange 122, the lower edge of which is spaced from the metallic plate 117, providing a narrow annular opening 123 through which air 60 may readily enter and find its way to the breather opening 40 in spindle 5. Very little oil can be splashed through this narrow opening 123 and due to the fact that the oil shield is rotating with the spindle 5, any oil that may enter through space 123 is immediately ejected by centrifugal force. This oil shield is very effective in preventing oil from splashing into the breather hole of the nozzle.

In ordinary operation of the device, the hydraulic pressure of the soap in chamber 81 may be some place between 500# and 1000# per square inch. Quantities of soap caused by this pressure to flow up past stuffing box 87 are trapped by groove 92 and conducted through holes 95 into 75 outer groove 96 which outer groove 96 registers

with a series of holes 99 through which the soap is free to pass to the outside of the nozzle body.

By the time that the soap has reached groove 92, the pressure has been reduced to that merely required to force the soap through the vents. Any soap that may pass groove 92 will, of course, be trapped in groove 93, thence through holes 94 to outer grooves 97 and thence through vent openings 98.

However, it has been found in practice that the 10 quantity of soap which passes groove 92 and finds its way to groove 93 is so small and under so little pressure that it does not pass leather washer 101 which is in actual contact fit with pin 88. In the modification of the invention now under discussion, conical end 13 of the spindle 5 terminates at end 103. The conical end 13 is tapered along a straight line forming a cone having an apex angle of approximately 60° in conjunction with a similarly conical shaped recess 12 in the plate 9. A 20 tapered surface clearance of about .012" to .015" has been found satisfactory in practice. The clearance between the small diameter 103 and the spindle 5 of the extrusion opening 11 determines the thickness of the extruded tube. In making 25 tube soap I have found a clearance of about .0043" satisfactory.

It will be readily apparent that other variations and modifications of the present invention may be devised without departing from the spirit of this 30 invention as defined in the following claims.

I claim:

1. An extrusion die for extruding semi-liquid material under hydraulic pressure comprising a 35 housing having a chamber for the reception of plastic semi-liquid material under hydraulic pressure and provided with an extrusion orifice and a spindle rotatable in said housing having a rotating extrusion pin located centrally of the orifice, said extrusion pin and the walls of the 40 orifice presenting smooth surfaces to the material and permitting a continuous uninterrupted flow of the material under hydraulic pressure, the said pin being held for rotation in the precise center of said orifice.

2. An extrusion die for extruding semi-liquid material under hydraulic pressure comprising a 45 housing having a chamber for the reception of plastic semi-liquid material under hydraulic pressure, an extrusion orifice in said housing and a 50 spindle mounted in said housing and rotatable therein, said spindle provided with a pin adapted to rotate in said orifice and terminating at the outer end thereof, said pin and the walls of the orifice presenting smooth surfaces to the material 55 and permitting a continuous uninterrupted flow of the same under hydraulic pressure, the said pin being held for rotation in the precise center of said orifice.

3. An extrusion die for extruding semi-liquid 60 material under hydraulic pressure comprising a housing having a chamber for the reception of plastic semi-liquid material under hydraulic pressure, an extrusion orifice in said housing and a spindle mounted in said housing and rotatable 65 therein, said spindle provided with a pin integral therewith and adapted to rotate in said orifice, said pin and the walls of the orifice presenting smooth surfaces to the material and permitting a continuous uninterrupted flow of the same under 70 hydraulic pressure, the said pin being held for rotation in the precise center of said orifice.

4. An extrusion die for extruding semi-liquid material under hydraulic pressure comprising a 75 housing having a chamber for the reception of

- 5 plastic semi-liquid material under hydraulic pressure, an extrusion orifice in said housing and a spindle mounted in said housing and rotatable therein, said spindle provided with a pin integral therewith and adapted to rotate in said orifice, said spindle having an opening throughout its length whereby air may be passed entirely through said spindle and pin and the said pin and the walls of the said orifice presenting smooth surfaces to the material and permitting a continuous uninterrupted flow of the same under hydraulic pressure, the said pin being held for rotation in the precise center of said orifice.

10 5. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure and an inlet opening leading to said chamber, said spindle provided with a pin integral therewith and adapted to rotate in said orifice, said spindle and pin having an opening throughout their length and the said pin and the walls of the orifice presenting smooth surfaces to the material and permitting continuous uninterrupted flow of the same under hydraulic pressure, the said pin being held for rotation in the precise center of said orifice.

15 6. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber and a passage connecting said orifice and said chamber, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure, the said pin being held for rotation in the precise center of said orifice.

20 7. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber and a conical passage defined by one end of the spindle and a portion of the inner surface of said housing connecting said orifice and said chamber, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure, the said pin being held for rotation in the precise center of said orifice.

25 8. An extrusion die for extruding semi-liquid material under hydraulic pressure comprising a housing, an extrusion orifice in said housing, a spindle mounted in said housing and rotatable therein, means for rotating said spindle, a chamber in said housing for the reception of plastic semi-liquid material under hydraulic pressure, an inlet opening leading to said chamber and a conical passage defined by one end of the spindle and a portion of the inner surface of said housing connecting said orifice and said chamber, said spindle provided with a pin integral therewith and

30 9. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, a ball bearing mounted between said spindle and said housing, and a passage connecting said orifice and said chamber, said spindle provided with a pin integral therewith and adapted to be rotated in said orifice, said spindle and pin having an opening throughout their length and the pin and the walls of the orifice presenting smooth surfaces to the material and permitting continuous uninterrupted flow of the same under hydraulic pressure.

35 10. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, a ball bearing mounted between said spindle and said housing, the balls of said ball bearing being mounted in an open race, said open race communicating with said chamber and a passage connecting said orifice and said race, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure.

40 11. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, a ball bearing mounted between said spindle and said housing, the balls of said ball bearing being mounted in an open race, said open race communicating with said chamber and a passage defined by said spindle and said housing connecting said orifice and said race, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure.

45 12. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, a ball bearing mounted between said spindle and said housing, the balls of said ball bearing being mounted in an open race, said open race communicating with said chamber and a conical passage defined by one end of said spindle and a portion of said housing connecting said orifice and said chamber, said spindle provided with a pin integral therewith and

orifice and said race, said spindle provided with a pin integral therewith and adapted to rotate in said orifice, said spindle and pin having an opening throughout their length and the pin and the 5 walls of the orifice presenting smooth surfaces to the material and permitting continuous uninterrupted flow of the same under hydraulic pressure.

13. An extrusion die for extruding semi-liquid material under hydraulic pressure comprising a housing, a spindle mounted in said housing and rotatable therein, an extrusion orifice in said housing, a chamber in said housing for the reception of plastic semi-liquid material under hydraulic pressure, an inlet opening leading to said chamber, ball bearings mounted in said housing to carry said spindle, the balls of one of said ball bearings being mounted in an open race, said open race communicating with said chamber and 15 a conical passage defined by one end of said spindle and a portion of said housing, said conical passage connecting said orifice and said open race, said spindle provided with a pin integral therewith and adapted to rotate in said orifice, 20 said spindle and pin having an opening throughout their length and the pin and the walls of the orifice presenting smooth surfaces to the material and permitting continuous uninterrupted flow of the same under hydraulic pressure.
14. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, ball bearings mounted in said housing and carrying said spindle, one of said ball bearings being sealed from said chamber and a passage 25 connecting said chamber and said orifice, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure.
15. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, ball bearings mounted in said housing and carrying said spindle, one of said ball bearings being sealed from said chamber and a conical 30 passage communicating with said chamber and said orifice, said spindle provided with a pin integral therewith and adapted to rotate in said orifice, said spindle and pin having an opening throughout their length and the pin and the walls of the orifice presenting smooth surfaces to the material and permitting continuous uninterrupted flow of the same under hydraulic pressure.
16. An extrusion die for extruding semi-liquid material under hydraulic pressure comprising a housing, a spindle mounted in said housing and rotatable therein, a chamber in said housing for the reception of plastic semi-liquid material under hydraulic pressure, an inlet opening leading to said chamber, ball bearings mounted in 35 said housing and carrying said spindle, one of said ball bearings being sealed from said chamber and pin having an opening throughout their length.

ber and a conical passage communicating with said chamber and said orifice, said conical passage being defined by one end of said spindle and a portion of said housing, said spindle provided with a pin integral therewith and adapted to rotate in said orifice, said pin terminating at the outer end of said orifice, said pin and the walls of the orifice presenting smooth surfaces to the material and permitting continuous uninterrupted flow of the same under hydraulic pressure, 10 said spindle and pin having an opening throughout their length.

17. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, ball bearings mounted in said housing 15 and carrying said spindle, one of said ball bearings being sealed from said chamber by a bushing, a recess in said bushing, an outlet opening from said recess to the outer surface of said housing, and a conical passage communicating with said chamber and said orifice, said conical passage being defined by one end of said spindle and a portion of said housing, said spindle being provided with a pin integral therewith and adapted to rotate in said orifice, said pin terminating at 20 the outer end of said orifice, said pin and the walls of the orifice presenting smooth surfaces to the material and permitting continuous uninterrupted flow of the same under hydraulic pressure, 25 said spindle and pin having an opening throughout their length.

18. An extrusion die for extruding semi-liquid material under hydraulic pressure comprising a housing, an extrusion orifice in said housing, a spindle mounted in said housing and rotatable 30 therein, a chamber in said housing for the reception of plastic semi-liquid material under hydraulic pressure, an inlet opening leading to said chamber, ball bearings mounted in said housing and carrying said spindle, one of said ball bearings being sealed from said chamber by a bushing and an enlarged portion on said spindle, said enlarged portion being rotatable in said bushing, said bushing and enlarged portion being interposed between said chamber and said ball bearing, a recess in and around said bushing, an outlet opening from said recess to the outer surface of said housing, a nut in the end of the housing opposite the extrusion orifice in contact with said ball bearing whereby said ball bearing may act as a thrust 35 bearing as well as a radial bearing, and a conical passage communicating with said chamber and said orifice, said conical passage being defined by one end of said spindle and a portion of said housing, said spindle being provided with a pin 40 integral therewith and adapted to rotate in said orifice, said pin and the walls of the orifice presenting smooth surfaces to the material and permitting continuous uninterrupted flow of the same under hydraulic pressure, and said spindle 45 and pin having an opening throughout their length.

19. An extrusion die for extruding semi-liquid material under hydraulic pressure comprising a casing, an end plate in said casing, an extrusion 50 orifice in said end plate, a spindle mounted in said casing and rotatable therein, a chamber in said casing for the reception of plastic semi-liquid material under hydraulic pressure, an inlet opening leading to said chamber, ball bearings 55

- 75
- 75

mounted in said casing and carrying said spindle, one of said ball bearings being sealed from said chamber by a bushing and an enlarged portion on said spindle, said spindle being rotatable in said bushing, said enlarged portion and bushing being interposed between said chamber and said ball bearing, a recess in and around said bushing, an outlet opening through said bushing to said recess, an opening in said casing registerable 5 with said opening in said recess, a nut in the end of the casing opposite the said end plate, said nut being in contact with said ball bearing, whereby said ball bearing may act as a thrust bearing as well as a radial bearing, the other of 10 said ball bearings being mounted in said casing intermediate said chamber and said end plate, the balls of said last mentioned ball bearing being mounted in an open race, said race communicating with said chamber and with a chamber intermediate said last mentioned ball bearing and said end plate and a conical passage connecting said last mentioned chamber and said orifice, said conical passage being defined by one 15 end of the spindle and a portion of said end plate and said spindle having a pin portion rotating in the orifice and terminating at the outer end thereof, the pin portion and the walls of the orifice presenting smooth surfaces to the material and permitting continuous uninterrupted flow of the material under hydraulic pressure.

20. An extrusion die for extruding semi-liquid material under hydraulic pressure comprising a housing, an extrusion orifice in said housing, a spindle mounted in said housing and rotatable therein, a chamber in said housing for the reception of plastic semi-liquid material under hydraulic pressure, an inlet opening leading to said chamber, bearings on said spindle, a shoulder in said housing, one of said bearings riding upon 35 said shoulder and against the inner surface of said housing, the other of said bearings riding against the inner surface of said housing and a cover at one end of said housing, a driving end integral with said spindle and rotatable in a bushing in said cover, a gear mounted on said driving end, exteriorly of said housing, a pin on said spindle integral and rotatable in said orifice, the pin and the walls of the orifice presenting smooth surfaces to the material to permit continuous uninterrupted flow of the same under hydraulic pressure, a conical passage connecting 40 said chamber and said orifice and a breather opening throughout the length of said pin, spindle and driving end.

50 21. A construction as defined in claim 20 in which the pin is substantially semi-circular.

22. A construction as defined in claim 20 in which the pin is substantially web shaped.

55 23. An extrusion die for extruding semi-liquid material under hydraulic pressure comprising a housing, an extrusion orifice in said housing, a spindle mounted in said housing and rotatable therein, said spindle comprising an extrusion pin rotatable in said orifice, the pin and the walls of the orifice presenting smooth surfaces to permit continuous uninterrupted flow of material under hydraulic pressure, bearing shoulders on the spindle defining a chamber in said housing for the reception of plastic semi-liquid material 60 under hydraulic pressure, an inlet opening leading to said chamber, a cover for said housing rigidly affixed thereto, an opening in said cover, a boss on said cover surrounding said opening, a cap thereover, threaded to said boss, an opening in said cap, said cap and said boss defining a

stuffing box including a bushing, a shaft on said spindle rotatable in said stuffing box, and openings in the bearing shoulder on said spindle closest the orifice whereby material entering said chamber may pass to said orifice.

24. An extrusion die for extruding semi-liquid material under hydraulic pressure comprising a casing, an extrusion plate in said casing, a conical recess in said extrusion plate, said conical recess terminating in an extrusion orifice, a spindle mounted in said casing and rotatable therein, a chamber in said casing for the reception of plastic semi-liquid material under hydraulic pressure, an inlet opening leading to said chamber, ball bearings mounted in said casing and carrying said spindle, said ball bearings being separated by a bushing within said casing and being sealed from said chamber by a stuffing box, recesses in and around said stuffing box, outlet openings from said recesses to the outer 10 surface of said casing, a conical end on said spindle rotatable within said conical recess, said conical end and said conical recess defining a conical passage communicating with said chamber and said orifice, said spindle having a terminal pin 15 portion rotating in the orifice, the pin portion and the walls of the orifice presenting smooth surfaces to the material and permitting continuous uninterrupted flow of the same under hydraulic pressure, and an opening throughout the 20 length of said spindle.

25. An extrusion die for extruding semi-liquid material under hydraulic pressure comprising a casing, an extrusion plate in said casing, a conical recess in said extrusion plate, said conical recess terminating in an extrusion orifice, a spindle mounted in said casing and rotatable therein, a chamber in said casing for the reception of plastic semi-liquid material under hydraulic pressure, an inlet opening leading to said chamber, ball bearings mounted in said casing and carrying said spindle, said ball bearings being separated by a bushing within said casing and being sealed from said chamber by a stuffing box, recesses in and around said stuffing box, 35 outlet openings from said recesses to the outer surface of said casing, a conical end on said spindle rotatable within said conical recess, said conical end and said conical recess defining a conical passage communicating with said chamber and said orifice, said spindle having a terminal pin 40 portion rotating in the orifice, the pin portion and the walls of the orifice presenting smooth surfaces to the material and permitting continuous uninterrupted flow of the same under hydraulic pressure, and an opening throughout the 45 length of said spindle.

26. An extrusion die for extruding semi-liquid material under hydraulic pressure comprising a casing, an extrusion plate in said casing, a conical recess in said extrusion plate, said conical 50 recess terminating in an extrusion orifice, a spindle mounted in said casing and rotatable therein, a conical end on said spindle, said conical end adapted to rotate within said conical recess, and ball bearings in said casing supporting said 55 spindle, one of said ball bearings being interposed between a shoulder on said spindle and a nut in said casing, the other of said ball bearings being positioned between a shoulder on said 60 spindle and a washer, said washer being held in 65 said casing.

contact with said ball bearing by a stuffing box, said stuffing box including a leather washer for sealing said ball bearing from a chamber defined by said stuffing box and said extrusion plate for receiving plastic semi-liquid material under hydraulic pressure, the spindle having a terminal pin portion rotating in said orifice and the pin portion and the walls of the orifice presenting smooth surfaces to the material and permitting continuous uninterrupted flow of the same under hydraulic pressure.

27. An extrusion die for extruding semi-liquid material under hydraulic pressure comprising a casing, an extrusion plate in said casing, a conical recess in said extrusion plate, said conical recess terminating in an extrusion orifice, a spindle mounted in said casing and rotatable therein, a conical end on said spindle, said conical end adapted to rotate within said conical recess, ball bearings in said casing supporting said spindle, one of said ball bearings being interposed between a shoulder on said spindle and a nut in said casing, the other of said ball bearings being positioned between a shoulder on said spindle and a washer, said washer being held in contact with said ball bearing by a stuffing box, said stuffing box including a leather washer for sealing said ball bearing from a chamber defined by said stuffing box and said extrusion plate for receiving plastic semi-liquid material under hydraulic pressure, said spindle having a terminal pin portion rotatable in the said orifice, the pin portion and the walls of the orifice presenting smooth surfaces to the material and permitting continuous uninterrupted flow of the same under hydraulic pressure, recessed grooves on the inner

surface of said stuffing box, said grooves communicating with the outer surface of said stuffing box by openings and openings in said casing registerable with said last mentioned grooves, said grooves being positioned below said leather washer.

28. An extrusion die for extruding semi-liquid material under hydraulic pressure as defined in the claim last preceding in which the shoulders on said spindle support the ball bearings at spaced points defining an enlarged portion on said spindle and a stuffing box in said casing in which said enlarged portion is rotatable, said stuffing box extending from bearing to bearing and being equal in length to said enlarged portion.

29. An extrusion die comprising a casing for the reception of plastic material under pressure provided with an extrusion orifice, a spindle rotatable in said casing at the precise center thereof, an extrusion pin integral with said spindle and rotatable at the precise center of said extrusion orifice, and means to hold said spindle and said extrusion pin for rotation at such precise center.

30. An extrusion die comprising a casing for the reception of plastic material under pressure provided with an extrusion orifice, a spindle rotatable in said casing at the precise center thereof, an extrusion pin integral with said spindle and rotatable at the precise center of said extrusion orifice, and means to hold said spindle and said extrusion pin for rotation at such precise center, said spindle and extrusion pin having a breather hole therethrough.

CHARLES T. WALTER.
